Patented Feb. 4, 1919.

UNITED STATES PATENT OFFICE.

FREDERIC WM. ERICKSON, OF NEW YORK, N. Y.

MARINE STRUCTURE.

1,293,063.

Specification of Letters Patent. Patented Feb. 4, 1919.

Application filed August 14, 1918. Serial No. 249,792.

To all whom it may concern:

Be it known that I, FREDERIC WM. ERICKSON, a citizen of the United States, residing at New York, in the county of New York and State of New York, have invented certain Improvements in Marine Structures, of which the following is a specification.

The present invention relates to composite reinforced marine structures to be partly immersed in water, such as barges, ships, etc., in which the immersed or submersible portion is made of reinforced concrete and the major portion out of water is of wood or metal.

15 By such composite construction of barges and ships they are produced at lower cost than when made all of wood or steel, much stronger than of wood and last longer than of all wood or steel, and practically fire-proof.

Concrete bottoms do not require painting if the outer surface is properly treated, and do not become fouled easily, and being heavier than steel or wood add to the stability of the vessel. If the upper portion only is of wood or steel shorter beams and girders can be used, thus saving valuable lumber, and the vessel can be constructed in shorter time, valuable considerations at the present time.

30 In carrying out my invention I use reinforced concrete for the keelson and bottom of the hull up to and including the bilge for the central part; at the forward end of the hull the reinforced concrete is carried up vertically to make the stern construction, and aft vertically to make the stern after deck and poop-deck.

In the drawings which form a part of the specification and to which reference is made—

Figure 1 is a horizontal section of a vessel showing the invention.

Fig. 2 is a cross-section of the hull.

45 Fig. 3 is an enlarged cross-section of a portion of the hull at the joint between the reinforced concrete forming the bottom of the hull and the wooden sides, and

50 Fig. 4 illustrates a portion of cross-section of a hull at a point between the reinforced concrete bottom at the line of the bilge and a steel upper section.

Referring to Fig. 1, A is a reinforced

concrete bottom stem and stern of a hull, B, having planking and superstructure of wood or steel C. c is the rudder of any commercial type; D is the propeller connected to the engine E by means of the propeller shaft J resting in the bearing blocks 1, 2, 3, etc. The boiler plant F is connected to the stack H in the usual manner. There is nothing unusual in the arrangement of the parts just referred to except their location on the concrete surface of the hull bottom, which constitutes an admirable foundation.

55 In Fig. 2, A is the reinforced concrete bottom, B the hull and planking, C², C², vertical timbers or struts, G, G, are stringers holding the frame-work of the hull to the concrete A. H², H², are framing knees supporting the deck timbers I on the vertical hull framing C. J is the propeller shaft in the alley K. L is the reinforced concrete main keelson. M and N are side keelsons and O the flooring of the cargo hold.

60 In Fig. 3, A is the reinforced hull, B² the hull planking above the bilge. a, a, are rods in the concrete to reinforce the same, and extend athwart ships in the bottom, and are connected at either end with holding down bolts c², by means of joints or eyes b, b. d is a sleeper bolted to the concrete base of the hull by the series of bolts c², c²; the joint between the sleeper and the concrete is made secure by the metal key f, running the entire length of the sleeper. To make the joint water-tight and to give an even bearing surface between the wood sleeper and the concrete, asphalt, mastic E² or other suitable seal is installed.

65 In Fig. 4, A is the reinforced concrete section, B³ the steel hull plating, C³ are vertical steel ribs bolted to the concrete base by means of a steel angle bar D² held securely in place by the hold down bolts c³, c³, etc.; which are secured to reinforcing rods a, a, etc., in the concrete base by means of the joints or eyes at the points b, b, etc.

70 The joint between the steel angle bar and the concrete is made secure and water-tight by any suitable plastic material indicated by the heavy line e e.

I claim as my invention:

75 1. A marine vessel having the lower portion of its hull composed entirely of reinforced concrete with substantially straight

edges, sleepers anchored to said edges, and a superstructure of lighter sectional material secured to said sleepers.

2. A marine vessel having the lower portion of its hull composed entirely of reinforced concrete with substantially straight edges, heavy wood sleepers anchored to said edges, and a wood superstructure secured to said sleepers.

opies of 1

In testimony whereof, I have signed my name to this specification in the presence of two subscribing witnesses, this 10th day of August, 1918.

FREDERIC WM. ERICKSON.
